WORK-HOLDING VISE

John Watson Robertson, London, England

Application December 30, 1940, Serial No. 372,465
In Great Britain January 9, 1940

7 Claims. (Cl. 81—36)

This invention relates to workholding vises of the kind in which the screw co-operates with a half-nut capable of being moved into and out of engagement with the screw by means of a cam or other device operating to displace the half-nut positively in both directions. The invention provides improved means whereby the half-nut is actuated as a consequence of the rotation of the screw.

According to this invention an additional screwthread is formed on a part of the screw spindle which is normally unthreaded and this additional screwthread co-operates with a nut which is operatively connected to the half-nut so that rotation of the screw spindle causes the nut to move lengthwise of the spindle to engage or disengage the half-nut according to the direction of rotation of the spindle.

Preferably, the device which actuates the half-nut consists of a cam movable lengthwise of the screw spindle and directly connected to the nut so that the cam is pushed by the nut in one direction or the other according to the direction of rotation of the spindle.

Referring to the accompanying drawings,

Figure 1 is a vertical sectional view of one embodiment of the invention,

Figure 2 is a view similar to Figure 1 showing the parts in a different position.

Figure 3 is a horizontal sectional view on the line III—III in Figure 1,

Figure 4 is a transverse sectional view on the line IV—IV in Figure 3, and

Figure 5 is a view similar to Figure 1 showing a modification.

Referring to Figures 1 to 4, the movable jaw 10 of the vise has a longitudinal extension 12 which slides within the body 14 of the vise having the fixed jaw 16 cast integral with it. The screw spindle 18, provided with a handle 19 carried in bearings in the extension 12, engages with a half-nut 20 which slides vertically in guides 22 forming part of the body 14 of the vise. The half-nut 20 is bored to receive an actuating bar 24 the ends of which are bent as at 26, 28 to constitute cams, the bent portions sliding in inclined holes 30, 32 respectively in the end walls of the extension 12. Figure 1 shows the half-nut 20 engaged with the screw spindle 18, the cam bar 24, 26, 28 having been moved to the left, and Figure 2 shows the half-nut disengaged from the screw spindle in consequence of the cam bar having been moved to the right.

The normally unthreaded part of the screw spindle 18 at the left-hand end as viewed in Fig-

ures 1 to 3 is formed with a multi-start screw-thread 34 of quick pitch, flanked on both sides by unthreaded portions 36, 38, the diameter of which is not greater than the core diameter of the thread 34. Co-operating with the thread 34 is a nut 40 having a downward extension 42 engaging in a slot 44 in the bar 24, the length of the slot being such as to provide lost motion between the nut 40 and the bar 24. A light coil spring 46 is interposed between the nut 40 and a shoulder 48 at the left of the unthreaded portion 36 and a similar spring 50 is provided which abuts against a collar 52 fixed to the spindle 18 at the right of the unthreaded portion 38.

Assuming that the parts are in the position shown in Figure 1 with the jaws gripping a work-piece 54, if the screw is turned counterclockwise as seen from the left to loosen the grip of the jaws, the screwthread 34 will engage the screw-thread within the nut 40, the nut being urged to the right by the spring 46, and will drive the nut to the right, the nut of course being held against rotation by the engagement of the extension 42 in the slot 44. This motion continues until the extension 42 encounters the right-hand end of the slot 44 whereupon the bar will be pushed to the right and owing to the slope of the cam portions 26, 28 the bar will move downwards as well as to the right, thereby disengaging the half-nut 20 from the screw spindle 18 as shown in Figure 2.

Normally the operator would cease turning the screw after this has happened because he can then move the movable jaw to any position merely by sliding it in or out. If, however, he should continue to turn the screw the nut 40 will move still further to the right until it is clear of the screwthread 34 and rides freely upon the unthreaded portion 38 of the spindle. Thus, it is impossible for the parts to be jammed or damaged by unnecessary turning of the screw spindle in the counterclockwise direction.

It will be appreciated that when the spindle is turned in the clockwise direction the converse will take place; the nut, being urged to the left by the spring 50, will at once engage the screw-thread 34 and will be driven to the left thereby pushing the bar 24 to the left and re-engaging the half-nut 20 with the screw spindle 18. Here again, owing to the fact that the nut 40 has moved clear of the screwthread 34 and rides freely upon the unthreaded portion 36, the screw spindle can be turned further to tighten the jaws upon the workpiece without having any further effect upon the nut 40 or the bar 24, while at the

same time, as already explained, the nut becomes re-engaged with the screwthread 34 immediately the direction of the screw spindle is reversed.

Referring now to Figure 5, the slope of the cam portions 26, 28 is reversed as compared with Figure 1, and the hand of the screwthread 34 is also reversed, being left-handed instead of right-handed. The device operates in exactly the same way except that the nut 40 and the bar 24 move to the right to bring the half-nut 20 into engagement with the screw spindle 18, and to the left to disengage it.

It may be desired to put the disengaging mechanism out of action so that the half-nut 20 is always in engagement with the screw spindle 18. For this purpose a slide 56 is provided which is guided in slots 58 in the sides of the extension 12 and is formed with a hook 60 which engages with the extension 42 of the nut 40 when the slide is moved to the right as seen in Figure 4. This hook then maintains the nut 40 out of engagement with the screwthread 34 and also prevents the bar 24 from moving to the right. Thus, the half-nut 20 remains in engagement with the screw spindle 18.

I claim:

1. The combination with a work-holding vise having a half-nut mounted in guides to move into or out of engagement with the screw spindle, of means for automatically engaging or disengaging the half-nut as a consequence of the rotation of the screw spindle comprising an additional screwthread formed on a part of the screw spindle which is normally unthreaded, a nut co-operating with said additional screwthread and an operative connection between the said nut and the said half-nut.

2. The combination with a work-holding vise having a half-nut mounted in guides to move into or out of engagement with the screw spindle, of means for automatically engaging or disengaging the half-nut as a consequence of the rotation of the screw spindle comprising an additional screwthread formed on a part of the screw spindle which is normally unthreaded, a nut co-operating with said additional screwthread and an operative connection between the said nut and the said half-nut, a portion of the spindle adjacent said additional screwthread being left unthreaded and of a diameter not greater than the core diameter of the threaded portion, to receive the nut after the screw spindle has been rotated by a certain amount in the tightening direction, whereby further rotation of the spindle in that direction has no further action on the nut.

3. The combination with a work-holding vise having a half-nut mounted in guides to move into or out of engagement with the screw spindle, of means for automatically engaging or disengaging the half-nut as a consequence of rotation of the screw spindle comprising an additional screwthread formed on a part of the screw

spindle which is normally unthreaded, said spindle having an unthreaded portion adjacent the additional screwthread of a diameter not greater than the core diameter of the threaded portion, a nut co-operating with the additional screw spindle, an operative connection between the said nut and the said half-nut whereby rotation of the screw spindle by a certain amount in the tightening direction causes the half-nut to engage the screw spindle and the nut to disengage itself from the additional screwthread, and a coil spring surrounding the screw spindle and adapted to be slightly compressed by the nut after it has become disengaged from the additional screwthread.

4. The combination with a work-holding vise having a half-nut mounted in guides to move into or out of engagement with the screw spindle, of means for automatically engaging or disengaging the half-nut as a consequence of the rotation of the screw spindle comprising an additional screwthread formed on a part of the screw spindle which is normally unthreaded, a nut co-operating with said additional screwthread and an operative connection between the said nut and the said half-nut, portions of the spindle adjacent said additional screwthread at either end thereof being left unthreaded and of a diameter not greater than the core diameter of the threaded portion, to receive the nut after the screw spindle has been rotated by a certain amount in either direction, whereby further rotation of the spindle has no further action on the nut.

5. A work-holding vise according to claim 4 wherein two coil springs, one on each of the unthreaded portions of the screw spindle, are adapted to be slightly compressed by the nut after it has become disengaged from the additional screwthread at either end.

6. The combination with a work-holding vise having a half-nut mounted in guides to move into and out of engagement with the screw spindle, of a cam device movable in a direction lengthwise of the screw and adapted to displace the half-nut positively in both directions, and means for automatically engaging or disengaging the half-nut as a consequence of the rotation of the screw spindle comprising an additional screwthread formed on a part of the screw spindle which is normally unthreaded, a nut co-operating with said additional screwthread and an operative connection between the said nut and the said cam device.

7. A work-holding vise according to claim 6, wherein the cam device comprises a bar having a straight middle portion parallel to the screw spindle and extending through a bore in the half-nut and having end portions bent to form cams sliding in inclined apertures in the movable part of the vise.

JOHN WATSON ROBERTSON.
